UNITED STATES PATENT OFFICE.

FREDERICK SCHWARTZ, OF BROOKLYN, NEW YORK, ASSIGNOR TO ROBERT FINDLAY MANUFACTURING COMPANY, INC., OF BROOKLYN, NEW YORK, A CORPORATION OF NEW YORK.

DESIGN FOR A BENCH.

Application filed August 10, 1928. Serial No. 27,786 Term of patent 7 years.

To all whom it may concern:

Be it known that I, FREDERICK SCHWARTZ, a citizen of the United States, and a resident of the borough of Brooklyn, city of New York, county of Kings, and State of New York, have invented a new, original, and ornamental Design for Bench, of which the following is a specification, reference being had to the accompanying drawing, forming a part thereof.

Figure 1 of said drawing is an end view of a bench showing my new design.

I claim:

The ornamental design for a bench, as shown.

FREDERICK SCHWARTZ.
